UNITED STATES PATENT OFFICE

GEORGE B. TIMBERLAKE, OF PINE LAWN, MISSOURI, ASSIGNOR TO EVA M. TIMBERLAKE, OF PINE LAWN, MISSOURI

WALL CONSTRUCTION AND HOLLOW BLOCKS THEREFOR

Application filed November 6, 1926. Serial No. 146,704.

This invention relates to new and useful improvements in wall construction and hollow blocks therefor, the objects of the invention being to provide hollow blocks which 5 may be utilized in building hollow walls and which, if desired, may be partly filled with concrete to form solid wall portions.

Other objects of the invention are to provide hollow building blocks having beveled 10 edges, thereby permitting the edges of the adjoining blocks to be brought close together with the binding material disposed in the V-shaped groove formed by the adjoining beveled edges.

Other objects of the invention are to form 15 the edges of each block with portions adapted to enter into interlock with the corresponding portions of the adjoining block, thereby assisting in the proper spacing of the blocks 20 and interlocking the latter against displacement.

Still further objects of the invention are to provide a novel method of building construction consisting in forming the wall of 25 hollow blocks, the interior of each block being divided by partition walls into separate vertically disposed chambers open at top and bottom and filling certain chambers of the blocks with concrete to form solid vertically 30 disposed wall portions.

With these and other objects in view, my invention consists in certain novel features 35 of construction and arrangement of parts, hereinafter more fully described and claimed, and illustrated in the accompanying drawings, in which—

Figure 1 is a top plan view of one form of my improved hollow block.

Figure 2 is an end view of same.

Figure 3 is a vertical section taken on line 40 3—3 of Figure 1.

Figure 4 is a vertical section taken transversely on line 4—4 of Figure 1.

Figure 5 is an enlarged detail view showing 45 the joint formed by the beveled edges of two adjoining blocks.

Figure 6 is a fragmental horizontal cross section of a solid wall built by means of my improved blocks.

Figure 7 is a fragmental horizontal cross 50

section through a wall utilizing a modified form of my blocks, wherein air chambers are provided.

Figure 8 is a fragmental horizontal section 55 through a modified form of the block showing embedded in any one of the side walls thereof a face plate or insert for the purpose of giving the desired finish to the face of the block.

Referring by numerals to the accompanying drawings, 10 indicates a hollow block having side walls 11, end walls 12, and intermediate transverse walls 14, the latter being spaced a suitable distance from the end walls to form a central chamber A and end chambers B, said chambers being vertically disposed and open at top and bottom. End walls 12 are spaced inwardly from the ends of side walls 10 so that portions of the latter project beyond said end walls as indicated at 10°. The edges of all the walls are beveled as indicated at 15, the inclined faces being presented inwardly toward each other with the exception of end walls 12 whose beveled portions are presented outwardly toward portions 10° as indicated at 15°. The edges 11 do not terminate in sharp points but are formed with flat portions 16 so that when the edges of two adjoining blocks are brought together, said flat portions 16 are brought in close contact with each other to form an inconspicuous meeting line and prevent the binding material, such as concrete 17, from entering between said faces 16. The beveled faces 15 cooperate with each other to form a V-shaped groove for receiving the marginal or binding material 17.

Each edge 15 is provided with an outwardly projecting lug 18 and an inwardly disposed recess 19, the latter being arranged adjacent to lug 18. Lugs 18 and recesses 19 are arranged in a predetermined order so as to allow the blocks 10 to be arranged in superimposed spaced relation and thereby break the vertical joints of the adjacent courses. 90 Lugs 18 and recesses 19 not only serve to space the blocks in proper relation but also provide an interlock for the blocks so as to hold the latter against displacement before and during the pouring of concrete. The 95

edges of end walls 12 and intermediate walls 14 are further formed with outwardly presented notches 20 which when the blocks are in position provide clearance for reinforcing rods 21 which are horizontally disposed in the wall as shown in Figure 6. However, the use of these rods may be dispensed with if desired.

In the form shown in Figure 6 both chambers A and B are completely filled with concrete, thereby forming a solid concrete wall.

In the form shown in Figure 7 a modified form of block 23 is used having side walls 24, end walls 25, transverse walls 26, and longitudinally disposed intermediate walls 27. The latter are spaced a suitable distance from side walls 24 to form chambers *a* and *b*, while chambers *a'* and *b'* are formed by said walls 27 and transverse walls 26 and end walls 25.

In the construction of this wall chambers *a* and *b* and chambers C, the latter formed by the abutting ends of adjacent blocks, are filled with concrete, thereby tying the blocks together and providing a substantially solid wall with air chambers *b'*. Chambers *a'* are also filled with concrete, being disposed in line with chamber C of the adjacent course of blocks. This latter form of wall construction is particularly desirable in the construction of larger buildings having walls of greater thickness and requiring greater strength. In this form of construction, air spaces are provided in the wall and at the same time a considerable saving of the concrete or other filling material is effected thereby.

In the construction of corners, the corner blocks are provided with an end wall 10^e which is formed flush with the ends 10^a of the block.

The blocks are so constructed that they form, by means of lugs 18 and recesses 19, an interlock with the block of adjacent courses, while the abutting ends are held together by the building material, such as mortar or concrete which fills the recesses formed in said ends.

By the use of blocks of my improved construction, walls may be constructed which are either hollow or solid, or partly solid and partly hollow as desired. Provision is made for the reception of horizontally disposed reinforcing rods and vertically disposed reinforcing rods may be used if desired.

The blocks may be made of any desired material and the faces of the blocks can be given any ornamental finish desired.

While I have shown and described the preferred forms of my invention, it is obvious that changes could be made in the shape and size of the blocks and in the construction of the wall without departing from the spirit of my invention.

I claim:

1. A hollow building block comprising in combination side walls, end walls spaced inwardly from the ends of said side walls, and a plurality of intermediate walls extending between said side walls, the edges of all of said walls having beveled edges, the edges of said side walls being beveled inwardly, whereby the abutting edges of the adjoining blocks form inwardly presented V-shaped mortar joints and provide a close contact on the exterior, each block being provided with partition walls dividing the interior of each block into a series of vertically disposed chambers open at top and bottom and adapted to be filled with concrete to bind the blocks together.

2. A building block having its walls formed with beveled edges terminating in flat abutment faces, thereby forming V-shaped mortar joints between the edges of the adjoining blocks, the flat abutment faces are left free of the mortar and form close contact with each other.

3. A building block having its walls formed with beveled edges, the apices of which terminate in flat abutment faces, whereby the mortar is disposed in V-shaped grooves formed by the adjoining blocks and the flat abutment faces are left free of said mortar and form close contact with each other, said blocks being divided by integral partition walls into vertically disposed chambers open at top and bottom, certain of which are adapted to be filled with concrete while the others are left open to provide air chambers therein.

4. A wall construction consisting of hollow blocks, the side walls of which are formed with inwardly beveled edges terminating in flat abutment faces to form inwardly presented V-shaped mortar joints between the adjoining blocks and form exteriorly a close joint between the meeting faces thereof, said blocks being provided with partition walls to form a plurality of vertically disposed chambers open at top and bottom, certain of said chambers being adapted to be brought into register with the chambers of the superimposed blocks and are adapted to receive concrete, binding said blocks together and providing a continuous concrete column, and reinforcing steel rods horizontally disposed between the horizontal rows of said blocks, the edges of the transverse walls of the latter being provided with notches for receiving said rods.

In testimony whereof I hereunto affix my signature this 3rd day of November, 1926.

GEORGE B. TIMBERLAKE.
